UNITED STATES PATENT OFFICE.

ROBERT A. WALSH, OF CARBONDALE, PENNSYLVANIA.

CAR REPLACER.

Application filed September 11, 1923. Serial No. 662,129.

To all whom it may concern:

Be it known that I, ROBERT A. WALSH, a citizen of the United States, residing at Carbondale, in the county of Lackawanna and State of Pennsylvania, have invented certain new and useful Improvements in Car Replacers, of which the following is a specification.

This invention relates to car replacers and 10 it consists in the novel features hereinafter described and claimed,

The various types of car replacers now in general use are so shaped and constructed as to render their functional efficiency unsatisfactory and frequently dangerous. Among 15 such disqualifying detriments is the faculty of "kicking" and that is to say when the cars or engines begin to mount the replacer, the enormous weight applied has a tendency 20 to displace the replacer with relation to the track rail for the reason that ample provision is not made for securing the replacer in position. In many instances the replacer rests upon two ties only which gives the replacer 25 a very insecure base foundation, which permits the replacer to "kick" and cause accident when subjected to the weight of the rolling stock.

The present invention serves to overcome 30 this serious objection in that the replacer rests upon three ties and is in the general form of an elongated pyramid having at one side a wall which extends the full length of the base of the body of the replacer and 35 which is adapted to abut or hug the side surface of the web of the track rail when applied. The up portion of the replacer body is provided with a recess adapted to receive the edge portion of the head of the 40 rail and hence the replacer overcomes a major fault in the old type, by being built along lines simulating the side contour of the rail and when in position practically becomes part of the track rail.

45 Another feature of advantage in the present invention is its length combined with the pyramid shape. The commodious lines and dimensions thus afforded give the replacer great and stable firmness when in 50 position. The lengths of the end portions from the center, with the easy and uniform rise makes the replacer a great deal more efficient in use and materially lessens the ab-

ruptness of ascent, which in the older types of replacers are decided drawbacks.

Another object of the invention is to provide the body with spike openings so located that each set of openings be disposed across a tie. These sets of openings are three in number, one set being located in the vicinity 55 of each end of the body and one set midway between the ends thereof. In the intervals of space between the sets of openings the body is provided with depending lugs which fit between the track ties.

The present replacer possesses advantages in use over the older types in that they reduce the time consumed in re-railing engines and cars at least, seventy-five per cent, for when placed in position they will re-rail 60 the stock with one pull where heretofore it has been a matter of luck if re-railment was accomplished in less than ten or fifteen pulls and consuming from one to two hours of time. Such delay has caused traffic tie-up 65 of expense to the roads and inconvenient to the traveling public.

In the present invention the car replacing outfit consists of two members or bodies, one adapted to be applied to the outer side of 70 one track rail and the other to the inner side of the other track rail. Both members or bodies are substantially of the same design and configuration with the minor exception 75 that one body is designed to lift a wheel flange over the head of one rail and the other body is designed to lift the tread of the tire only of another wheel over the head of the other track rail.

In the accompanying drawings—

Figure 1 is a plan view of a track section with the car replacer bodies applied to the rails thereof.

Figure 2 is a transverse sectional view of one track rail and the replacer body used 85 at the outer side of said track rail.

Figure 3 is a similar view of the other track rail and the replacer body used at the inner side of such rail and Figure 4 is a detail face view of one of the two depending 100 carrying lugs with which both of the replacer bodies are equipped.

To facilitate the description of the invention the replacer body which is used at the outer side of the track rail is designated B, 105 and the body which is used at the inner side

of the rail A. Both of these bodies are of the same length and the same transverse breadth. The body B is taller than the body A and the slopes of its inclined sides are 5 slightly different angles from the slopes of the corresponding sides of the body A.

Both bodies are in the general form of elongated pyramids each having at one side a rail web abutting wall 1 which is disposed vertically to the base line 2 of the body. The upper edge of the wall 1 is beveled as at 3 to fit under the head of the track rail and the lower edge is bevelled as at 4 to rest upon the upper surface of the base 15 flange of the rail. The base 2 is recessed as at 5 to receive the edge portion of the base flange of the track rail. The wall 1 extends the full length of the replacer body and is offset from the intermediate portion thereof thereby providing the body at a point above 20 the upper edge of the wall 1 with a recess 6 adapted to receive the side portion of the head of the track rail.

Three spaced flanges 7 stand out from the base 2 at the opposite side of the body from that side at which the wall 1 is located and each flange is provided with a set of spike openings 8 whereby the body may be spiked to three of the ties of the track. The flanges 30 7 completely bridge the upper sides of the ties. One flange 7 is located at each end of the body and one flange at a point intermediate the ends of the body. At the same side, the body of the replacer is provided 35 with depending lugs 9 which lie in the spaces between the flanges and which are disposed at right angles to the base of the body. The lugs are provided with upwardly converging edge surfaces 10 and each lug is 40 provided with a hand opening 11. The lugs may be used for conveniently carrying the body and when the body is placed the lugs fit between the adjacent ties and serve to assist in holding the body firmly in position.

45 The body is elongated longitudinally at its peak thereby providing a crown portion 8'. An upstanding flange 9' extends from end to end of the body and along the crown 8' and at its inner side is provided with an inwardly inclined surface 12. The flange 9' is located at the upper edge of the body opposite that edge thereof at which the wall 1 is located. The end surfaces 13 are inclined from the base 2 up to the crown 8' and 50 are inclined downwardly from the inner edge of the surface 12 toward the wall 1. The top surface 14 is inclined downwardly from the intermediate portion of the flange 9' toward the recess 6. A bracing web 15 is disposed 55 under the upper sides of the body and joins integrally with the sides 13 and 14 and the base 2 along the median longitudinal dimensions thereof whereby the said web is disposed at an acute angle to the base 2 and at 60 an acute angle to the wall 1 and the side of

the body opposite said wall. A cross web 16 is disposed parallel with the base and spaced therefrom. The said web 16 is integrally joined with the wall 1 and the side of the body opposite the wall and the intermediate portion of the web 15.

70 The form B of the replacer is provided at the lower portion of its side surface 14 and above the recess 6 with a lip portion 17 which is adapted to lie over the top of the track rail and which will guide the wheel flange transversely across the head of the rail during the operation of replacing. The lower edge of the surface 14 of the form A when applied, is disposed at the side of the head of the other track rail and lifts the wheel flange so that the tread of the wheel tire may pass transversely over the head of the track rail during the operation of replacing.

75 Having described the invention what is claimed is—

1. A car replacer comprising a body in the general form of an elongated pyramid having at one side a rail web abutting wall which is disposed vertically to the base line 80 of the body, said wall extending the full length of the base of the body, the said body being provided at the same side with a rail head receiving recess located above the upper edge of the said wall and a lip portion disposed over the recess and adapted to lie upon the top of the head of the rail.

85 2. A car replacer comprising a body in the general form of an elongated pyramid having at one side a rail web abutting wall 90 which is disposed vertically to the base line of the body, said wall extending the full length of the base of the body, the said body being provided at the same side with a rail head receiving recess located above the upper edge of the said wall and a trinity of spaced flanges at the base of the opposite side and disposed in alinement with the plane of the base, said flanges having spike 95 openings.

100 3. A car replacer comprising a body in the general form of an elongated pyramid having at one side a rail web abutting wall which is disposed vertically to the base line 105 of the body, said wall extending the full length of the base of the body, the said body being provided at the same side with a rail head receiving recess located above the upper edge of the said wall and a trinity of spaced flanges at the base of the opposite side and disposed in alinement with the plane of the base, said flanges having spike 110 openings and lugs located in the spaces between the flanges and disposed below the base line of the body and perpendicular thereto and adapted to engage between track ties.

115 4. A car replacer comprising a body in the general form of an elongated pyramid having at one side a rail web abutting wall 120

which is disposed vertically to the base line of the body, said wall extending the length of the base of the body, the body being provided at the same side with a rail head receiving recess located above the upper edge of the said wall, the body having between its longer sides a web which extends the full length of the base of the body and which

is joined with the base at the median longitudinal dimension thereof and with the end and sides and the recessed side of the body along the median longitudinal dimensions thereof.

In testimony whereof I affix my signature.

ROBERT A. WALSH.
